UNITED STATES PATENT OFFICE.

DONALD R. BREWSTER, OF CINCINNATI, OHIO, ASSIGNOR TO THE STANDARD DRY KILN COMPANY, OF INDIANAPOLIS, INDIANA, A CORPORATION OF INDIANA.

KILN.

Application filed March 12, 1924, Serial No. 698,648.

To all whom it may concern:

Be it known that I, DONALD R. BREWSTER, a citizen of the United States, residing at Cincinnati, in the county of Hamilton and 5 State of Ohio, have invented a new and useful Improvement in Kilns, of which the following is a specification.

My invention relates to improvements in drying chambers, and particularly to chambers for drying lumber, and other forest 10 product, clay products, etc.

One of the objects of my invention is to provide a drying chamber in which the heat 15 may be evenly distributed throughout the entire chamber and in which the temperature and humidity at all points of the chamber may be maintained equal if desired, or, if desired, the temperature and humidity each may be varied for different portions of 20 the chamber, depending upon necessitating conditions.

Another object of my invention is to provide a drying chamber having an increased 25 capacity for a given space.

And still another object of my invention is to provide a drying chamber wherein the circulation of drying air through the stacks 30 of material is increased and wherein such circulation may be controlled for each stack of material.

For the purpose of disclosing my invention I have illustrated in the accompanying drawings, certain embodiments thereof. In 35 said drawings,

Fig. 1 is a perspective view of a lumber drying kiln embodying my invention;

Fig. 2 is a longitudinal section thereof, taken substantially through the center of one drying room;

Fig. 3 is a plan view of the radiator pit of a drying room or chamber;

Fig. 4 is a transverse section of a drying room, and

Fig. 5 is a detail section showing a modification.

In the embodiment illustrated, I have shown, in Fig. 1, a perspective view of a two chamber drying apparatus. As each chamber is constructed the same, it will only be necessary to describe the construction and arrangement of one chamber.

As shown, the chamber 1, is provided with the usual roof 2 and has doors arranged at each end of the chamber to permit the inser-

tion of the lumber in one end and removal 55 of the lumber from the other end. Each room is provided with air flues, or chimneys, 3, which communicate at their bottom, as at 4, with the chamber and open to the atmosphere at the top. Arranged longitudinally 60 of each chamber are tracks 5 on which are adapted to travel, the load-carrying trucks 6. Beneath these tracks is arranged the radiator pit, in which the heating pipes and steam jet pipes are all arranged, the tracks 65 being supported above the pipes on suitable standards or uprights 7.

The heating medium for the chamber comprises a plurality of radiator units 8 which are spaced apart from one another longitudinally of the chamber to form between the units, down draft flue-ways 9. Each radiator unit preferably comprises a group of steam pipes 10 which extend transversely of the kiln chamber and in each group there is 75 a series of pipes arranged one above the other and connected at each end with return bends or elbows 11 to form practically a series of coils arranged side by side. The upper end of the coil is connected to a supply 80 header 12 and the opposite end of the coil, at the bottom, is connected to a return header 13. Each of these supply and return headers is connected, respectively, by a supply pipe 14 and return pipe 15 to a main supply 85 16 and main return 17 provided with the usual steam traps, etc. Each of the supply pipes 14 is provided with a control valve 18 for controlling the admission of steam to the individual radiator units and likewise, each 90 of the return pipes 15 is provided with a control valve 19.

In each of the flue ways between the radiator units and extending transversely of the chamber, is mounted a steam pipe 20 having 95 at suitable intervals, openings 21 on its under side to form a series of jet nozzles arranged to project the steam downwardly toward the bottom of the chamber. Each of these pipes is connected by a supply pipe 22, 100 with a source of steam supply and is provided with a hand valve 23. A second steam jet pipe 24 for each radiator unit is arranged transversely of the chamber and above the unit. This pipe is provided with 105 openings 25 forming jet nozzles arranged to project the steam jet upwardly and this pipe is likewise connected with a suitable source

of steam supply and provided with a hand valve 26.

At each end of the chamber there are also provided, small warming radiator units 27 and 28, constructed similarly to the main radiator units, but preferably having a fewer number of coils and the supply and return headers are each provided with a supply pipe 29 and return pipe 30 connect-
ed, respectively, with the supply main 16 and with the return main 17 and provided respectively, with controlling valves 31 and 32.

At the bottom of the radiator pit and at one side thereof, there is provided an air flue 33 extending the length of the chamber and having opposite each radiator unit, an outlet opening 34. A steam supply pipe 35 extends the length of this flue and is provided with jet nozzles 36, one for each of the openings 34, which nozzles are arranged to project through these openings.

Each of the trucks 6 is adapted to carry a lumber stack 37 and the lumber is stacked on the truck in such a manner as to provide a vertical flue way 38. The lumber is stacked by what is commercially known as cross-wise piling so that when it is run into the chamber the boards extend transversely of the chamber. Each truck is positioned immediately above a radiator unit so that the space between the stacks forms a downwardly extending flue forming a continuation of the down draft flue 9. between the radiator units, and the flue ways 38 form up draft flue ways above the radiator unit so that the heated air from the unit will rise through the flue way 38, passing out between the boards of the lumber stack, which are stacked in the usual manner with stickers between the same. The air having been cooled in its passage through the lumber stack will, by the time it reaches the outer side of the stack, tend to drop downwardly between the stacks. The downwardly projecting steam jets from the steam pipes 20 cause a partial vacuum above the jets and in the down draft flue ways to accelerate the circulation of the air and at the same time impart sufficient moisture to the air to provide the proper amount of humidity. In addition to the downwardly projecting steam jets, I may also use the upwardly projecting steam jets in the pipes 24 which, when in use, will assist the upward draft of the heated air through the flue ways 38 in the lumber stack.

It will be noted from the above described construction that I provide a unit circulation for each stack and that, due to the fact that the radiator and steam jet units extend transversely of the chamber, I am enabled to control the heat and humidity at any point within the chamber or for any

individual stack, whereby I am enabled to obtain a better heating control throughout the entire chamber and the danger of the far end of the chamber becoming chilled due to the lack of supply of a proper amount of steam to this end, as is the case where the radiator units extend longitudinally of the chamber, is obviated.

In Fig. 6 I have illustrated a modification of my invention wherein, in order to increase the circulation, I have provided baffles 40 arranged partially over the top of each radiator unit and extending downwardly to about the bottom of the unit, whereby an open topped flue way, enclosing the unit, is provided.

It is obvious that with my construction, any number of radiator units may be used, depending of course, upon the length of the heating chamber.

I claim as my invention:

1. A drying apparatus, including a chamber, load carriers movable within and longitudinally of said chamber and a plurality of radiator units extending transversely of the chamber at the bottom thereof and spaced apart longitudinally of the chamber to form between them, vertical down draft flue ways extending transversely of the chamber, each load carrier being located immediately above a radiator unit and supporting the material in stacks extending transversely of the chamber to form between the stacks continuations of said transversely extending down draft flue ways.

2. A drying apparatus, including a chamber, load carriers movable within and longitudinally of said chamber, a plurality of radiator units extending transversely of the chamber at the bottom thereof and spaced apart longitudinally of the chamber to form between the units vertical down draft flue ways extending transversely of the chamber, each load carrier being located immediately above a radiator unit and supporting the material in stacks extending transversely of the chamber to form between the stacks continuations of said transversely extending down draft flue ways and means for individually controlling the heat of each radiator unit.

3. A drying apparatus, including a chamber, load carriers movable within and longitudinally of said chamber, a plurality of radiator units extending transversely of the chamber at the bottom thereof and spaced apart longitudinally of the chamber to form between them vertical down draft flue ways extending transversely of the chamber, a plurality of steam jet nozzles arranged in each of said flue ways and adapted to direct the jet downwardly, each load carrier being located immediately above a radiator unit and supporting the material in stacks ex-

- tending transversely of the chamber to form between the stacks continuations of said transversely extending down draft flue ways.
5. 4. A drying apparatus, including a chamber, load carriers movable within and longitudinally of said chamber, a plurality of radiator units extending transversely of the chamber at the bottom thereof and spaced apart longitudinally of the chamber to form between the units vertical down draft flue ways extending transversely of the chamber and steam jet nozzles arranged above each radiator unit and adapted to 10 direct the jet upwardly, each load carrier being located immediately above a radiator unit and supporting the material in stacks extending transversely of the chamber to form between the stacks continuations of 15 said transversely extending down draft flue ways.
5. A drying apparatus, including a chamber, load carriers movable within and longitudinally of said chamber, a plurality of 20 radiator units extending transversely of the chamber at the bottom thereof and spaced apart longitudinally of the chamber to form between them vertical down draft flue ways extending transversely of the chamber, and steam jet nozzles arranged in each of said down draft flue ways and adapted to direct the jet downwardly, each load carrier being located immediately above a radiator unit and supporting the material in stacks having vertical transversely 25 extending up draft flue ways over the radiator unit and forming between the stacks continuations of said transversely extending down draft flue ways.
5. A drying apparatus, including a chamber, load carriers movable within and longitudinally of said chamber, a plurality of 30 radiator units extending transversely of the chamber at the bottom thereof and spaced apart longitudinally of the chamber to form between them vertical down draft flue ways extending transversely of the chamber, and steam jet nozzles arranged in each of said 35 flue ways and adapted to direct the jet downwardly and steam jet nozzles arranged above each of said radiator units and adapted to direct the steam jet upwardly, each load carrier being located immediately above a radiator unit and supporting the material in stacks extending transversely of the chamber to form between the stacks continuations of said transversely extending 40 down draft flue ways.
6. A drying apparatus, including a chamber, load carriers movable within and longitudinally of said chamber and a plurality of radiator units extending transversely of the chamber at the bottom thereof and spaced apart longitudinally of the chamber to form between them vertical down draft flue ways extending transversely of the chamber, each of said load carriers being located immediately above a radiator unit and supporting the material in stacks having transversely extending vertical up draft flue ways above the radiator units, and forming between the stacks continuations of said transversely extending down draft flue ways.
7. A drying apparatus, including a chamber, load carriers movable within and longitudinally of said chamber, a plurality of 50 radiator units extending transversely of the chamber at the bottom thereof and spaced apart longitudinally of the chamber to form between them vertical down draft flue ways extending transversely of the chamber, and means for independently controlling said 55 transversely extending down draft flue ways.
8. A drying apparatus, including a chamber, load carriers movable within and longitudinally of said chamber, a plurality of radiator units, each load carrier being located immediately above a radiator unit and supporting the material in stacks having vertical transversely extending up draft flue ways over the radiator unit and forming between the stacks continuations of said transversely extending down draft flue ways.
9. A drying apparatus, including a chamber, load carriers movable within and longitudinally of said chamber, a plurality of radiator units extending transversely of the chamber at the bottom thereof and spaced apart longitudinally of the chamber to form between them vertical down draft flue ways extending transversely of the chamber, and steam jets arranged above each of said radiator units, each load carrier being located immediately above a radiator unit and supporting the material in stacks having vertical transversely extending up draft flue ways over the radiator unit and forming between the stacks continuations of said vertical down draft flue ways.
10. A drying apparatus, including a chamber, load carriers movable within and longitudinally of said chamber, and a plurality of radiator units extending transversely of the chamber at the bottom thereof and spaced apart longitudinally of the chamber to form between them vertical transversely extending down draft flue ways, steam jet nozzles located above each of said radiator units and arranged to direct the steam upwardly and steam jet nozzles arranged in each of said vertical flue ways and arranged to direct the steam jet downwardly, each load carrier being located immediately above a radiator unit and supporting the material in stacks having vertical transversely extending up draft flue ways over the radiator units and forming between the stacks continuations of said vertical down draft flue ways.
11. A drying apparatus, including a chamber, load carriers movable within and longitudinally of said chamber, and a plu-

5 rality of radiator units, each unit comprising a group of steam pipes extending transversely of the chamber at the bottom thereof, the units being spaced apart longitudinally of the chamber to form between them vertical transversely extending down draft flue ways, each load carrier being located immediately above a radiator unit and supporting the material in stacks extending transversely of the chamber to form between the stacks continuations of said transversely extending down draft flue ways.

12. A drying apparatus, including a chamber, load carriers movable within and longitudinally of said chamber, a plurality of radiator units, each unit comprising a group of steam pipes extending transversely of the chamber at the bottom thereof, and means for independently controlling the admission of steam to each group of pipes, said units being spaced apart longitudinally of the chamber to form between them vertical down draft flue ways extending transversely of the chamber and each load carrier being located immediately above a radiator unit and supporting the material in stacks extending transversely of the chamber to form between the stacks continuations of said transversely extending down draft flue ways.

13. A drying apparatus, including a chamber, load carriers movable within and longitudinally of said chamber, a plurality of radiator units, each unit comprising a group of steam pipes extending transversely of the chamber, said units being spaced apart longitudinally of the chamber to form between them transversely extending down draft flue ways, steam pipes extending transversely of the chamber in said flue ways and having jet nozzles arranged to project the steam downwardly, and means for controlling the admission of steam to said steam jet pipes independently of each other and independently of the heating pipes and each load carrier being located immediately above a radiator unit and supporting the material in stacks extending transversely of the chamber to form between the stacks continuations of said transversely extending down draft flue ways.

14. A drying apparatus, including a chamber, load carriers movable within and longitudinally of said chamber, a plurality of radiator units each comprising a group of steam pipes extending transversely of the chamber, said groups being spaced apart longitudinally of the chamber to form between the groups vertical transversely extending down draft flue ways, steam pipes arranged above said groups having steam jet nozzles arranged to direct the steam upwardly, and means for independently controlling the admission of steam to each of said groups of heating pipes and to said jet

70 pipes, said load carriers being located immediately above a radiator unit and supporting the material in stacks extending transversely of the chamber to form between the stacks continuations of said transversely extending down draft flue ways.

15. A drying apparatus, including a chamber, load carriers movable within and longitudinally of said chamber, a plurality of radiator units each comprising a group 75 of steam pipes extending transversely of the chamber, said groups being spaced apart to form between them transversely extending vertical down draft flue ways, a steam pipe arranged in each of said flue ways having jet nozzles for directing a steam jet downwardly in said flue ways, a steam pipe arranged over each of said groups having jet nozzles arranged to direct a steam jet upwardly and means for independently controlling the admission of steam to each of said heating groups and each of said jet pipes, each load carrier being located immediately above a radiator unit and supporting the material in stacks extending 90 transversely of the chamber to form between the stacks continuations of said transversely extending down draft flue ways.

16. A drying apparatus, including a chamber, load carriers movable within and longitudinally of said chamber, a plurality of radiator units extending transversely of the chamber at the bottom thereof and spaced apart longitudinally of the chamber to form between them vertical down draft 100 flue ways extending transversely of the chamber, each load carrier being located immediately above a radiator unit and supporting the material in stacks extending transversely of the chamber to form between the stacks continuations of said transversely extending down draft flue ways and means for heating the chamber at the entry thereof.

17. A drying apparatus, including a chamber, load carriers movable within and longitudinally of said chamber, a plurality of radiator units extending transversely of the chamber at the bottom thereof and spaced apart longitudinally of the chamber 115 to form between them vertical down draft flue ways extending transversely of the chamber, each load carrier being located immediately above a radiator unit and supporting the material in stacks extending 120 transversely of the chamber to form between the stacks continuations of said transversely extending down draft flue ways, and means for heating the chamber at the exit thereof.

18. A drying apparatus, including a chamber, load carriers movable within and longitudinally of said chamber, a plurality of radiator units extending transversely of the chamber at the bottom thereof and 130

spaced apart longitudinally of the chamber to form between them vertical down draft flue ways extending transversely of the chamber, each load carrier being located 5 immediately above a radiator unit and supporting the material in stacks extending transversely of the chamber to form between the stacks continuations of said transversely extending down draft flue ways, and means for heating the chamber at its 10 entry and exit.

In witness whereof, I DONALD R. BREWSTER, have hereunto set my hand at Indianapolis, Indiana, this 2nd day of March, A. D. one thousand nine hundred and twenty-four.

DONALD R. BREWSTER.
